UNITED STATES PATENT OFFICE.

ANDERSON W. CARMICHAEL, OF SAVANNAH, GEORGIA.

METHOD OF MANUFACTURE OF ROSIN SOAP AND THE LIKE.

No. 908,951.

Specification of Letters Patent.

Patented Jan. 5, 1909.

Application filed October 16, 1907. Serial No. 397,652.

To all whom it may concern:

Be it known that I, ANDERSON W. CARMICHAEL, a citizen of the United States, and a resident of Savannah, in the county of 5 Chatham and State of Georgia, have invented a new and Improved Method of Manufacture of Rosin Soap and the Like, of which the following is a full, clear, and exact description.

10 This invention is an improved method for de-hydrating a saponified solution of rosin, commonly called "wet pulpy size," in the production of hard rosin soap, which is more especially used by paper mills in the 15 so-called sizing or waterproofing process.

Prior to my invention, the manufacture of rosin soap, without the addition of an excess of soda, carbonate of soda or other equivalent compound, has been confined to 20 soft soap containing from forty to sixty per cent. or more, of water. This soap necessarily has to be packed in the better class of hard wood and waterproof barrels, whereas the soap produced by my process 25 permits of its shipment in a condensed state in cheap pine wood boxes or barrels in which the rosin has been and is still being shipped, in addition to offering a considerable saving in freight, as substantially no water is 30 transported.

Reference is to be had to the accompanying drawings forming a part of this specification, in which similar characters of reference indicate corresponding parts in both 35 views.

Figure 1 is a vertical central sectional view through an apparatus for the production of hard rosin soap and the like by my improved method; and Fig. 2 is a plan of 40 the same.

An apparatus for carrying out my process comprises a cooking vessel 5 of suitable capacity, preferably of cylindrical form and surrounded by a steam jacket 6, 45 the latter being provided with a steam supply 7. Journaled in the center of the vessel is a vertical shaft 8, having affixed thereto slightly below the top of the vessel, a series of radiating arms or blades providing a beater 9, and also with a pulley or other suitable driving means 10, fixed above the 50 heater.

Connecting with the bottom of the vessel 5 through a pipe 11, is a rotary pump 12,

which discharges through a pipe 13, having 55 the discharge end thereof overhanging the vessel above the beater 9. The apparatus is also preferably provided with a supply pipe 14, for introducing the size into the vessel. 60

In carrying out my improved method, a mixture of certain proportions of rosin in its crude state, and alkali, is introduced into the vessel and brought to the state of saponification by the steam in the steam jacket. To 65 this is added the usual proportion of water, and is commonly known as "wet pulpy size," which is used for the so-called sizing or waterproofing process by the mills producing paper. When the size has been consistently 70 heated to the point where it starts to foam, the foam beater 9 is set in action, beating down the foam as it rises, keeping it from running over the top and to waste, and thus liberating the vapor; at the same time the 75 rotary pump 12 is started and pumps the size from the bottom of the tank through the outlet or discharge pipe 11 and discharges the size into the top of the tank above the beater, thereby providing a continuous flow from the 80 bottom to the surface of the liquid, which facilitates the evaporation of the water. This operation is continued until substantially no water remains, when the resulting product on cooling will be found to be a 85 hard rosin soap or size of superior quality, entirely uniform in strength, purity and solubility.

Having thus described my invention, I claim as new and desire to secure by Letters 90 Patent:

1. The herein-described method of producing hard rosin soap, which consists in heating a saponified solution of rosin and striking the foam rising at the surface of said 95 solution to break the bubbles and liberate the vapor.

2. The herein described method of producing hard rosin soap, which consists in heating a saponified solution of rosin, beating down the foam rising at the surface of said solution to liberate the vapor and prevent the overflow of the foam, and withdrawing said solution from the under surface and discharging it over the surface thereof. 100

3. The herein described method of producing hard rosin soap, which consists in heating within a vessel a saponified solution 105

of rosin, beating down the foam rising at the
surface of said solution to liberate the vapor
and prevent the foam from overflowing the
vessel, and withdrawing said solution from
the bottom of the vessel and discharging it
therein over the surface of the solution.

In testimony whereof I have signed my

name to this specification in the presence of
two subscribing witnesses.

ANDERSON W. CARMICHAEL.
